UNITED STATES PATENT OFFICE.

MOÏS H. AVRAM, OF NEW YORK, N. Y., ASSIGNOR TO AVRAM-LEET ENGINEERING COMPANY,
OF NEW YORK, N. Y., A CORPORATION OF NEW YORK.

KILN.

No. 888,573.

Specification of Letters Patent.

Patented May 26, 1908.

Application filed July 19, 1907. Serial No. 384,518.

To all whom it may concern:

Be it known that I, Moïs H. AVRAM, a citizen of the United States, residing at New York, county of New York, State of New York, have invented certain new and useful Improvements in Kilns, of which the following is a full, clear, and exact description.

My invention relates to improvements in kilns or cylinders such as are used for drying various materials or for hardening sand lime brick and the like, and has for its object to provide a cylinder or kiln with opening and closing means, which can be more conveniently manipulated than the means used at present, and also to provide a cylinder in which unhardened bricks can be supplied at one end and hardened bricks taken out from the other end.

My invention broadly considered, so far as the closing means is concerned, consists of an end piece formed of a frame and a cover proper carried thereby, in combination with any suitable means for removing this frame and cover from the end of the cylinder, by a movement at an angle to its axis, and means for forcing the cover away from the frame and into engagement with the end of the cylinder so as to make a tight engagement therewith. Various means may be provided for moving the frame and for forcing the cover proper away from the frame, and the direction of movement of the frame may also be modified. I prefer, however, to use the pressure means which are hereafter described, and to move the frame together with the cover vertically upward and downward.

The following is a description of an embodiment of my invention, reference being had to the accompanying drawing, in which Figure 1 is a side elevation of a cylinder, Fig. 2 is a cross section of the same, showing the bricks in position, Fig. 3 is an end elevation of the same, Fig. 4 is a longitudinal section of the closing means at one end, and Fig. 5 is a section showing details.

Referring more particularly to the drawing, A is a cylinder constituting a receiving chamber which for brick hardening kilns is in practice made some five to seven feet in diameter and thirty to eighty feet long. In this cylinder and running its entire length, are car tracks B upon which can be moved a truck C carrying bricks D. The tracks are in line with external tracks B' at each end so that the truck can be moved into and out of

the cylinder as desired, temporary bridging rails being inserted for that purpose. The cylinder, when the hardening process is going on, usually contains a sufficient number of trucks to extend over the full length of the track. Means are provided for opening and closing the cylinder at each end so that unhardened bricks can be fed in at one end as they come from the press and be removed at the other end for storage or shipping.

Heretofore great difficulty has been experienced in closing the cylinders, even when one end only was open, and my closing means is intended to obviate this difficulty. This means consists of a yoke E preferably cast and having its lower portion provided with a circular opening which surrounds the end of the cylinder, as shown at E' E'. The outer end of the cylinder is provided with an upturned flange F which fits in a recess in the face of the yoke. The yoke is provided with an integral flange G and a removable flange G' forming a groove or runway for the movable head of the cylinder. The upper end of the yoke is provided with a cross-piece H through which passes a screw-threaded rod I, the screw-threads of which engage with the internal screw-threads on the hub J of a worm-wheel J'. This worm-wheel J' is driven by a screw K, which in turn is driven by any convenient source of power. A clutch K' may be used for connecting and disconnecting the worm from such source of power. To the lower end of the screw-threaded rod I is connected a cross-head L which carries a cylindrical disk or frame M provided with suitable strengthening ribs. On the inner side of the frame or disk M is a disk N which forms the head proper of the cylinder. This is provided with a projection 95 from which extends a rod N' surrounded by a compression spring N². The head N is movable relatively to the disk M, and when free to move outward is drawn in that direction by the compression spring N². Around the periphery of the head N pressure is exerted by sixteen pressure screws O having threads of steep pitch and carried by the disk M. Within each of these compression screws is an auxiliary adjusting screw O' of slow pitch for adjusting the pressure due to the rotation of the screws O upon bearing surfaces P of the head N.

O² is a lock nut for securing the auxiliary screws when once adjusted. The screws O

are each provided with angular portions on which fit quadrants Q provided with gear teeth q . Any two successive quadrants lie in different planes so as to overlap, and thus 5 not interfere with the action of one another. These quadrants all mesh with teeth upon a large gear wheel R loosely mounted upon a projection carried by the frame M. Attached to this large gear is a smaller gear S. 10 Rigidly connected to the projection on the frame M is a second small gear T having the same number of teeth as the gear S. Between these two gears a power wheel U, preferably a hand wheel, is loosely mounted upon 15 a projection, which power wheel carries a freely moving shaft U' on which are rigidly mounted two small gears V V'. These small gears have an unequal number of teeth, there being preferably one more tooth on one of 20 them than on the other. The result is that as the hand wheel U is turned, the gear S, together with the gear R, is moved the distance of one tooth for every revolution of the shaft U'. This motion is communicated to the 25 quadrants Q and thus a very slow but a very powerful movement is communicated to the screws O. The pitch of the screws O is so steep that a quarter of a revolution of the same will force the head P up snug against 30 the end of the cylinder, and, by reason of the backing p', form a substantially steam-tight joint around the cylinder. The outer flange G' of the yoke acts as an abutment for the frame M to hold it in position against the 35 pressure of the screws O, and permits an even pressure to be applied at frequent intervals to the entire circumference of the inner head M. The lip M' engaging the yoke also assists in holding the frame in position. 40 Casings or covers W W' may be provided for the gears and moving parts other than the hand wheel U. A similar closing means is provided at both ends of the cylinder A. When it is desired to charge the cylinder, the 45 hand wheel U is revolved until the pressure due to the screws O is removed. The worm K is then operated until the cover is elevated so as to uncover the end of the cylinder. The cars are then rolled in until the cylinder 50 is filled, whereupon the end piece is lowered by a reverse movement of the worm K and the cover is forced against the end of the cylinder so as to make a steam-tight joint by manipulating the hand wheel U. The parts 55 necessarily have large weight in order to get sufficient strength, but by the means described they can be easily handled and the desired closure effected. It is to be noted that the pressure upon the cover proper is 60 applied at its periphery and at equal intervals, so that the strain upon the cover due to the pressure screws is well distributed and is directly over the circumferential bearing.

The apparatus is simple and effective and 65 enables a great saving of both time and labor

over closing means heretofore used. It admits of various modifications without departing from the broad principles involved, and various equivalents can be substituted for devices shown without departing from the 70 spirit of my invention.

What I claim is:

1. In a kiln, the combination of a receiving chamber, a yoke adjacent to the mouth thereof, a frame carried by said yoke and held from movement longitudinal to the chamber, a cover carried by the frame and located between the frame and the mouth, means for forcing the cover away from the frame and toward the mouth, and means for 80 moving the frame together with the cover in a direction at an angle to the axis of the chamber.

2. In a kiln, the combination of a receiving chamber, a yoke adjacent to the mouth thereof, a frame carried by said yoke and held from movement longitudinal to the chamber, a cover carried by the frame and located between the frame and the mouth, means for forcing the cover away from the 85 frame and toward the mouth, said means engaging the periphery of said cover, and means for moving the frame together with the cover in a direction at an angle to the axis of the chamber.

3. In a kiln, the combination of a receiving chamber, a yoke adjacent to the mouth thereof, a frame carried by said yoke and held from movement longitudinal to the chamber, a cover carried by the frame and located between the frame and the mouth, means for forcing the cover away from the frame and toward the mouth, said means being carried by said frame and engaging the periphery of said cover, and means for moving the frame together with the cover in a direction at an angle to the axis of the chamber.

4. In a kiln, the combination of a receiving chamber, a yoke adjacent to the mouth thereof, a frame carried by said yoke and held from movement longitudinal to the chamber, a cover carried by the frame and located between the frame and the mouth, means for forcing the cover away from the frame and toward the mouth, said means consisting of set screws carried by the frame and engaging the periphery of said cover, and means for moving the frame together with the cover in a direction at an angle to the axis of the chamber.

5. In a kiln, the combination of a receiving chamber, a yoke adjacent to the mouth thereof, a frame carried thereby and held from movement longitudinal to the chamber, a cover carried by the frame and located between the frame and the mouth, means for forcing the cover away from the frame and toward the mouth, said means consisting of set screws carried by the frame and engaging 130

the periphery of said cover, means for moving the frame together with the cover in a direction at an angle to the axis of the chamber, and toothed sectors carried by said set 5 screws and a common gear carried by said frame, and with which said sectors mesh.

6. In a kiln, the combination of a receiving chamber, a yoke adjacent to the mouth thereof, a frame carried thereby and held 10 from movement longitudinal to the chamber, a cover carried by the frame and located between the frame and the mouth, means for forcing the cover away from the frame and toward the mouth, said means consisting of 15 set screws carried by the frame and engaging the periphery of said cover, means for moving the frame together with the cover in a direction at an angle to the axis of the chamber, toothed sectors carried by said set 20 screws and a common gear carried by said frame with which said sectors mesh, a power wheel, and reducing gearing located between said hand wheel and said common gear.

7. In a kiln, the combination of a receiving 25 chamber, a yoke adjacent to the mouth thereof, a frame carried thereby and held from movement longitudinal to the chamber,

a cover carried by the frame and located between the frame and the mouth, means for forcing the cover away from the frame and 30 toward the mouth, said means consisting of portions bearing on said cover at frequent intervals, and means for simultaneously acting upon said portions to cause them to engage and disengage said cover. 35

8. In a kiln, the combination of a receiving chamber, a yoke adjacent to the mouth thereof, a frame carried thereby and held from movement longitudinal to the chamber, a cover carried by the frame and located 40 between the frame and the mouth, means for forcing the cover away from the frame and toward the mouth, said means consisting of set screws carried by the frame and engaging 45 the periphery of said cover, together with adjusting screws passing through said set screws, means for simultaneously revolving said set screws, and means for moving the frame together with the cover at an angle to the axis of the chamber.
